Attorney

UNITED STATES PATENT OFFICE.

EDWARD LEACH, OF RATHMEL, PENNSYLVANIA.

ELECTRIC SWITCH FOR MINES.

1,257,255.

Specification of Letters Patent. Patented Feb. 19, 1918.

Application filed April 12, 1917. Serial No. 161,454.

To all whom it may concern:

Be it known that I, EDWARD LEACH, a citizen of the United States, residing at Rathmel, in the county of Jefferson, State of

5 Pennsylvania, have invented a new and useful Electric Switch for Mines; and I do hereby declare the following to be a full, clear, and exact description of the invention, such as will enable others skilled in the art
10 to which it appertains to make and use the same.

The present invention relates to an automatic cut-out switch for use in connection with line and trolley wires, the switch embodying novel features of construction whereby the current will be automatically cut-off in the event the wire is subjected to an abnormal pull or breaks, thereby eliminating the possibility of fire or accident due
15 to a live wire.

Further objects of the invention are to provide an automatic cut-out switch of this character which is compact in its construction, which is thoroughly dependable in its operation, which does not interfere in any manner with the passage of a trolley wheel along the wire, and which can be installed without difficulty at any point.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawing, in which:—

Figure 1 is a side elevation of an automatic cut-out switch constructed in accordance with the invention, parts being broken away and shown in section, and the switch parts appearing in operative position so that there will be an uninterrupted flow
40 of current through the switch.

Fig. 2 is a similar view, the switch parts being shown as actuated to interrupt the flow of current.

Fig. 3 is a side elevation of the cut-out
50 switch.

Fig. 4 is a transverse sectional view on the line 4—4 of Fig. 1.

Fig. 5 is a view similar to Fig. 1, showing a slight modification, one end of the
55 switch being broken away.

Fig. 6 is a top plan view of the switch.

Corresponding and like parts are referred to in the following description and indicated in all the views of the drawings by the same reference characters.

60

Referring to the drawings, the numeral 1 designates the switch body which is formed of some suitable insulating material, such as wood, and which is shown as having a hollow formation. A metal end piece 2 is secured to one end of the switch body 1 and formed with a longitudinally extending guide opening 3 within which a slide 4 is mounted, the outer end of the slide terminating in a head 5 to which the trolley or line wire 6 is secured. In a similar manner a metal end-piece 7 is secured to the opposite end of the switch body 1 and electrically connected to the feed wire 8 from which current is received from a suitable source of supply. In the present instance this feed wire 8 is shown as connected to a block 9 which is insulated from the end-piece 7 by an interposed member 10, the end-piece 7 and block 9 being normally placed in electrical connection by a knife blade switch 11. An arm 12 projects downwardly from the blade of the switch 11 and carries a plate 13 which is flush with the lower face of the device, and electrically connects the lower end of the end-piece 7 to the lower end of the block 9. This provides a smooth lower surface for the trolley wheel, and also carries the current from the block 9 to the end-piece 7 so that there will be no danger of burning out the switch 11.

A switch terminal block 14 is let into the top of the body 1 so that a notch 14^a in one side thereof is exposed within the hollow interior of the body, the upper end of the terminal block 14 projecting above the switch body and being connected by a conducting wire 15 to the end-piece 7. The before mentioned slide 4 is pivotally connected at its inner extremity to the lower end of an upright switch operating lever 16, said lever being pivotally mounted at an intermediate point between its ends upon a pivot pin 17 which extends transversely across the interior of the hollow switch body, and being engaged at its upper end by a compression spring 18. This spring 18 is of just sufficient strength to resist the normal pull of the wire 6, and in the event of an abnormal pull, such as would be occasioned by a cave-in within a mine, the spring 18 would yield and permit the switch oper-

110

ating lever 16 to swing upon its pivot 17. A laterally projecting trip finger 19 carried by the upper end of the switch operating lever 16 will then engage an upright trip lever 20 which is also mounted upon the pivot pin 17, and swing the trip lever to pull the end of a swinging arm 21 out of engagement with the notch 14^a of the switch terminal block 14. This arm 21 is normally 10 horizontally disposed and is pivotally connected to the end of the trip lever 20, the middle portion of the arm being longitudinally slotted at 22 to receive a lateral pin 23 projecting from the upper end of a crank 15 24 which carries a switch plate 25. A spring 26 may engage the arm 21 for forcibly 20 swinging the same downwardly as soon as the free end thereof is disengaged from the notch 14^a of the switch terminal block 14. The switch plate 25 normally provides a 25 direct electrical connection between the lower faces of the end-pieces 2 and 7, being constructed for coöperation therewith to provide a smooth and uninterrupted track 30 for the trolley wheel. However, as soon as the arm 21 is disengaged from the notch 14^a and swung downwardly by the spring 26, as indicated by Fig. 2, the plate 25 is lowered into inoperative position, thereby 35 breaking the direct electrical connection between the end-pieces 7 and 2. The electrical connection through the top wire 15, terminal block 14, arm 21 and other parts of the switch mechanism, is also broken, so that 40 the wire 6 becomes dead and there is no danger of a fire or accident in connection therewith.

The construction shown by Figs. 1 to 4 of the drawings is especially adapted for 45 use in mines, since it is designed to cut off the current automatically in the event of a cave-in. The normal pull of the wire 6 is resisted by the compression spring 18, of the switch actuating lever 16, although a 50 cave-in would cause an abnormal pull upon the wire 6 and overcome the resistance of the spring 18, thereby causing the trip mechanism to disengage the swinging arm 21 from the notch 14^a of the switch terminal block 14 and completely cut-off the flow 55 of current from the feed wire 8 to the wire 6. The position assumed by the parts when the cut-out mechanism has been actuated to interrupt the current is shown by Fig. 2, while the normal position of the parts is 60 shown by Fig. 1. One end of the trip pin 19 at the upper end of the switch operating lever 16 will preferably project through a curved slot 27 in one side of the hollow switch body, the movements of the trip pin 65 within the slot 27 enabling an operator to determine when the wire 6 is under proper tension.

A slight modification is shown by Fig. 65 5, in which the switch operating lever 16^c

is engaged at its lower end by a tension spring 18^c which operates to resist the tension in the wire 6. The trip pin 19^c at the upper end of the switch operating lever 16 is arranged on the opposite side of the trip lever 20^c, and the swinging arm 21^c terminates in a hooked end 21^d adapted to engage a notch 14^c in the far side of the switch terminal block 14. With this construction the cut-out switch will be automatically operated in the event the line wire 6 breaks. The pull of the wire being thus released, the tension spring 18^c will swing the switch operating lever 16^c and cause the trip finger 19^c to swing the trip lever 20^c, thereby disengaging the hooked end 21^d of the swinging arm 21^c from the notched switch terminal block 14. The spring 26 will then forcibly pull the arm 21^c downwardly, thereby breaking the electrical connection through the terminal block 14 and the arm 21^c, and also causing the switch plate 25 at the lower end of the hanger 24 to be moved downwardly into inoperative position. The general idea of construction is the same as in 90 the previous instance, although the parts are arranged to operate the cut-out when the wire breaks, instead of when there is an abnormal pull thereon.

Having thus described the invention, what 95 I claim as new and desire to secure by Letters Patent, is:—

1. An automatic cut-out switch for line wires, including a switch operating lever operatively connected to the line wire, resilient means acting upon the switch operating lever to resist the normal action of the line wire thereon, a bodily movable switch plate normally establishing direct electrical connection between the source of current 100 supply and the line wire, a swinging trip arm normally holding the switch plate in operative position, and means actuated by the switch operating lever for releasing the trip arm and causing the switch plate to 105 move into inoperative position.

2. An automatic cut-out switch for line wires, including a switch operating lever operatively connected to the line wire, resilient means acting upon the switch operating lever to resist the normal action of the line wire thereon, a trip finger projecting from the said lever, a trip lever arranged in the path of the trip finger, a notched support, an arm connected to the trip lever and normally having the free end thereof engaged by the notched support, and a hanger 115 pend- 120 ent from the swinging arm and connected to the switch plate to hold the latter in operative position, the actuation of the trip 125 means and disengagement of the free end of the arm from the notched support causing the switch plate to be moved into inoperative position.

3. An automatic cut-out switch for line 130

wires, including a switch operating lever operatively connected to the line wire, resilient means acting upon the switch operating lever to resist the normal pull of the line wire thereon, a notched switch terminal block in electrical connection with the source of current supply, a trip lever, a swinging arm having one end thereof connected to the trip lever while the opposite end thereof closely engages the notched switch terminal block, current being then conveyed through the terminal block, arm and parts associated therewith, to the line wire, and means upon the switch operating lever for swinging the trip lever to disengage the arm from the notched switch terminal block when the tension in the line wire becomes abnormal.

4. An automatic cut-out switch for line wires, including a switch operating lever operatively connected to the line wire, resilient means acting upon the switch operating lever to resist the pull of the line wire thereon, a notched switch terminal block in electrical connection with the source of current supply, a trip lever, a swinging arm pivotally mounted upon the trip lever and normally engaging the notch of the switch terminal block, means upon the switch operating lever for swinging the trip lever to disengage the swinging arm from the notched terminal block, a switch plate for normally producing a direct electrical connection between the source of current supply and the line wire, and an operative connection between the switch plate and the swinging arm for moving the switch plate into inoperative position when the swinging arm is disengaged from the switch terminal block.

40 5. An automatic cut-out switch for line wires, including an insulated switch body, metal end pieces applied to opposite ends of the switch body, one of the end pieces being in electrical connection with the source of current supply, while the opposite end piece is provided with a longitudinal guide, a slide mounted within the longitudinal guide and having the line wire connected to the outer end thereof, an upright switch operating lever mounted upon the insulated body and connected to the inner end of the slide, yielding means acting upon the switch operating lever to resist the pull of the line

wire thereon, a notched switch terminal block arranged upon the insulated body and electrically connected through the end piece with the source of current supply, a trip lever, a swinging trip arm pivoted at one end upon the trip lever and adapted to have the other end thereof in normal engagement with the notched switch terminal block, and a trip pin upon the switch operating lever for engaging the trip lever to swing the same and disengage the arm from the notched terminal block.

6. An automatic cut-out switch for line wires, including an insulated switch body, metal end pieces applied to opposite ends thereof, one of the end pieces being provided with a longitudinal guide, while the opposite end piece is connected to the source of current supply, a slide mounted within the longitudinal guide and connected at its outer end with the line wire, an upright switch operating lever mounted upon the insulated body and pivotally connected to the inner end of the slide, yielding means acting upon the switch operating lever to resist the normal pull of the line wire, a notched switch terminal block mounted upon the insulated body and connected through the end piece with the source of current supply, a trip lever, a swinging arm pivotally connected at one end to the trip lever and adapted to have the other end thereof in normal engagement with the notched switch terminal block, a trip pin upon the switch operating lever for engaging the trip lever to swing the latter and disengage the arm from the notched switch terminal block, a switch plate arranged to produce direct electrical connection between the before mentioned metal end pieces, and a hanger pendent from the swinging arm and carrying the switch plate so that the switch plate is moved into inoperative position when the arm is disengaged from the switch terminal block.

In testimony whereof I have signed my name to this specification in the presence of two subscribing witnesses.
